UNITED STATES PATENT OFFICE.

MARTIN B. MC LAUTHLIN, OF MALDEN, MASSACHUSETTS.

ELEVATOR-CONTROLLING APPARATUS.

SPECIFICATION forming part of Letters Patent No. 621,970, dated March 28, 1899.

Application filed April 12, 1898. Serial No. 677,342. (No model.)

To all whom it may concern:

Be it known that I, MARTIN B. MC LAUTHLIN, of Malden, in the county of Middlesex and State of Massachusetts, have invented certain new and useful Improvements in Elevator-Controlling Apparatus, of which the following is a specification.

This invention relates to electric elevators and systems of control therefor.

It has for its object to provide improved controlling means for elevators; and to this end it consists in certain features of novelty in construction and arrangement, to be fully set forth in the succeeding description and the claims hereto appended with the aid of the accompanying drawings.

Figure 1 represents a side elevation of an elevator mechanism constructed in accordance with my invention, certain devices forming a part of the invention being omitted. Fig. 2 represents a top plan view thereof. Fig. 3 represents a section on line 3 3 of Fig. 1. Figs. 4 and 5 represent diagrammatic views showing different positions of the shipper-pulley and the rheostat. Fig. 6 represents a side view of the switch. Figs. 7 and 8 represent views, partly in plan and partly in diagram, showing the switch in its two positions and illustrating its connections with the motor, rheostat, and line. Fig. 9 represents a side elevation showing a modified construction of certain parts of the switch. Fig. 10 represents a top plan view of part of the elevator mechanism, illustrating a device for stopping the motor when the hoisting-cable slackens. Fig. 11 represents a side elevation of the same. Fig. 12 represents a detail plan view, which will be hereinafter referred to.

The same reference characters indicate the same parts in all the figures.

In the embodiment of my invention shown in the drawings and selected by me for the purpose of illustrating my invention a winding-drum and electric motor connected by the usual worm-gearing are employed, and a shipper-pulley operated by a shipper-rope which is controlled in a suitable manner from the car is used to move the controlling mechanism. As the winding-drum is driven by a worm connected with the motor-shaft, it is necessary to send a current through the motor to rotate its armature both in raising and

lowering the car, and to effect this a novel reversing-switch is used, the movable members of which are mounted directly on the 55 shipper-pulley. This switch is connected with the compound-wound motor in such a manner that in reversing the motion of the armature current is sent in the same direction through the field, but in a reverse direction 60 through the armature.

I employ as a novel feature a rheostat whose arm is operated by devices connected with both the hoisting mechanism and the shipper-pulley and which is arranged so that in starting the elevator-car from rest the shipper-pulley is first moved to close the switch with the full resistance of the rheostat in the armature-circuit. A relatively small current is thereby passed through the motor-armature 70 to start the motor, and as the latter gathers speed the arm of the rheostat is automatically moved by the action of the hoisting apparatus to gradually cut the resistance out of the armature-circuit until the full current 75 passes through the armature. In stopping the car the rheostat-arm is entirely controlled by the shipper-pulley.

A further feature of novelty in my invention is a stopping device under the control of 80 the hoisting-cable. If for any reason the elevator-car should become obstructed in the well while descending, the slackening of the cable automatically actuates this device and causes it to stop the motor. The device is arranged so that the motor can be started again 85 by the usual movement of the shipper-rope to raise the car.

Referring to the drawings, *a* is a base provided with standards *a'* *a'*, in which is journaled the shaft *b'* of the winding-drum *b*, the latter being here shown in two sections 2 3, on which are wound the two sections of a double hoisting-cable *b³* *b³*.

c is the driving-motor, having a shaft *c'*, on 90 an extension of which is mounted a worm *c²*, which engages the teeth of a worm-gear *b²*, mounted on the shaft of the winding-drum.

d is the shipper-pulley or controlling-sheave, operated by a shipper-rope *d¹⁸* and mounted 100 to rotate on a sleeve *d'*, which is secured in brackets *d²* *d²*, mounted on the frame of the apparatus.

e is a brake operated by means of a brake-

arm e' , which is shown in its lowest position in Fig. 1. The said brake-arm is adapted to be engaged and raised by either one of two roller-studs d^3 d^4 , mounted on the shipper-pulley d . When the hoisting apparatus is in motion, the rollers d^3 d^4 ordinarily stand vertically and maintain the brake-arm in a raised position, in which position the brake is thrown off and the motor-shaft is free to revolve. When the shipper-pulley is moved to open the switch, these rollers assume their horizontal position (shown in Fig. 1) and allow the brake-arm, which is provided with an adjustable weight e^2 , to descend and actuate the brake to stop the motor-shaft. During this movement the brake-arm and its weight materially assist in centralizing the shipper-pulley and throwing the switch open by reason of the downward pressure exerted on the stud d^3 , on which the brake-arm rests.

On the back of the shipper-pulley d are mounted two metal blades d^4 d^{14} , which form the movable members of the controlling-switch. The fixed members of said switch consist of two sets of contact-plates d^5 d^6 d^7 and d^8 d^9 d^{10} , mounted in brackets which project from the base a and are insulated from one another, and two contact-plates d^{11} d^{12} , to which one of the shunt-terminals of the motor is connected, as will be hereinafter explained. The blade d^4 on the shipper-pulley is arranged to pass between and electrically connect the switch-plates d^6 and d^7 or the plates d^9 d^{10} , depending upon the direction in which the elevator-car is to run. The blade d^{14} is arranged to connect the plates d^5 , d^6 , and d^{11} or the plates d^8 , d^9 , and d^{12} .

Through the center of the sleeve d' , on which the shipper-pulley is journaled, runs a shaft f . On this shaft is rigidly secured a friction-disk g , formed as a sprocket-wheel. Next to said disk and in frictional contact therewith is a second disk g' , loosely mounted on the shaft and also formed as a sprocket-wheel, and on the outer end of the shaft is splined an arm h . A third friction-disk g'' is splined to the shaft f between the disk g' and the brackets d^2 .

h' is a spring surrounding the shaft f and interposed between the arm h and the end of the sleeve d' . The tension of this spring is regulated by adjusting two lock-nuts h^2 h^3 and moving the shaft f and disk g longitudinally in or out, so that a means is afforded of varying the pressure and hence the amount of friction between the disks g and g' . The disk g' is connected by means of a chain i with a small sprocket-wheel j , affixed to the shaft b' of the winding-drum, the said disk being thereby constantly rotated when the winding-drum is in motion. The disk g is connected by means of a longer chain k with a sprocket-wheel m^2 , mounted on a shaft m' , which carries the movable arm m^3 of a rheostat m . The said rheostat has two segmental sets of contacts m^4 m^5 , upon one of which the arm m^3 operates when the motor-armature

turns in one direction, while it operates on the other set when said armature turns in the opposite direction.

70

A "lost-motion" connection between the shipper-pulley d and the shaft f is furnished by two pins or studs d^{15} d^{16} , secured to or formed on the shipper-pulley and constituting stops adapted to coöperate with the arm h , as hereinafter explained.

75

The motor c , which I have illustrated, is provided with compound winding and is connected to the switch and the rheostat in the following manner, as shown in Figs. 7 and 8: A wire 4 connects the contact-plates d^7 and d^{10} with one terminal of the series winding c' of the motor-field. The other terminal of said winding is connected to the line-wire 5 and to one terminal of the shunt-winding c^2 of the motor-field, the remaining terminal of the winding c^2 being connected by a wire 7 with the switch-plates d^{11} and d^{12} . The switch-plates d^5 and d^8 are connected to the line-wire 6. The switch-plate d^6 is connected by a wire 8 with one armature-brush c^3 , while the other armature-brush c^4 is connected by a wire 9 with the two upper end contacts of the rheostat m . The heel of the rheostat-arm m^3 operates on a metallic ring m^7 , which is connected by a wire 10 with the switch-plate d^9 .

90

Referring to Fig. 7 and supposing the current to be coming from the line in the direction of the arrow x , it will be seen that the current passes through the wire 6 and switch-plate d^8 to the contact-blade d^{14} . There it divides, part going through the switch-plate d^{12} , wire 7, shunt-winding c^2 , and wire 5 out onto the line and part through switch-plate d^9 , wire 10, rheostat m , winding of armature, wire 8, switch-plate d^6 , contact-blade d^4 , switch-plate d^7 , wire 4, series winding c' , and wire 5 out onto the line.

105

Referring to Fig. 8, in which the position of the switch has been reversed and the arm m^3 of the rheostat is on the other set of contacts, it will be noted that the current passes in the same direction as before through the windings of the field and in an opposite direction through the winding of the armature, as indicated by the direction of the arrows. This causes the armature to revolve in an opposite direction.

110

The operation of the mechanism is as follows: When the motor is stopped, the shipper-pulley is "centralized," so that the blades d^4 and d^{14} , carried by said shipper-pulley, have substantially a vertical position, and the arm h on the end of shaft f occupies a depending position between the pins d^{15} and d^{16} , substantially as shown in Fig. 1. The arm m of the rheostat occupies a corresponding depending position and is in contact with a long metal segment m^5 , interposed between the two lowermost contacts m^4 . When the rheostat-arm m^3 is in this position and current passes, the full resistance of the rheostat is in the armature-circuit, and as the arm moves up along one of the segments of contacts the resistance is

115

120

125

130

gradually cut out until said arm reaches a position such as shown in Fig. 5, when full current is supplied to the armature. Supposing, then, that the operator by moving 5 the shipper-pulley in a direction to raise the elevator-car throws it over to the left, the switch members then occupy the position shown in Fig. 8 and the motor is started with the full resistance of the rheostat in the ar- 10 mature-circuit. This causes the winding-drum b to revolve slowly at first, with its shaft rotating in the direction of the arrow y , Fig. 4, which produces a rotation of the disk g' through the medium of sprocket j and chain z . 15 The frictional contact of the disk g' with the disk g causes the latter to rotate, and motion is transmitted through the chain k in the direction of the arrow y' , Fig. 4, to the sprocket m^2 and the rheostat-arm m^3 , causing the latter to move upwardly along the right-hand segment of contacts m^4 and gradually cut the resistance out of the armature-circuit. When 20 said arm reaches the last contact, it is restrained from further motion either by coming in contact with a pin m^6 on the face of the rheostat or by reason of the arm h coming in contact with the pin d^{15} , as shown in Fig. 5, and causing the rotation of the shaft f and disk g to cease. The disk g' continues 25 to rotates and slips between the disks g and g^2 . When it is desired to stop the elevator-car, the operator manipulates the shipper-rope and moves the shipper-pulley d in the direc- 30 tion of the arrow z , Fig. 5. The current-sup- 35 ply is thereby cut off at the switch, and by reason of the engagement of the arm h by the pin d^{15} the rheostat-arm m^3 is moved downwardly until it reaches the contact m^5 , the shipper-pulley being then centralized, as 40 shown in Fig. 1. When it is desired to lower the elevator-car, the operations are the re- 45 verse of those above stated. The shipper-pulley is moved around to the right and the switch thrown to the position shown in Fig. 8, in which case the armature of the motor turns in a direction opposite to that in which it turned before, and the rheostat-arm m^3 is moved onto the left-hand segment of contacts m^4 by reason of the rotation of the friction- 50 disks in a direction reverse to their previous direction of rotation.

It will be noted on referring to Fig. 6 that the switch-plates d^5 and d^8 to, which the line-wire 6 is connected, are cut off at their lower 55 ends to make them shorter than the neighboring plates d^6 and d^9 . The short lower ends of said plates are also not diametrically opposite the upper ends of the plates d^6 , d^7 , d^8 , and d^{10} . The result of this construction, as 60 will be noted by observing the position of the contact-blades d^4 d^{14} in Fig. 6, is to cut the line off when opening the switch before breaking the internal circuits of the motor. In 65 this way I am enabled to discharge the field through a closed circuit and also to safely dispose of the electromotive forces, which result from the motor acting as a generator for

an instant before it stops. Thus, referring to Fig. 8 and supposing the blades d^4 d^{14} to be positioned as in Fig. 6, the plate d^5 , forming the line-terminal, is cut out; but there is still a complete circuit starting from blade d^{14} and going through shunt-terminal d^{11} , wire 7 , shunt-winding c^2 , series winding c' , wire 4 , plate d^{10} , blade d^4 , plate d^9 , wire 10 , rheostat m , wire 9 , motor-armature, wire 8 , and plate d^6 back to blade d^{14} . 70

It is clear that the switch-plates d^{11} and d^{12} , to which the terminal of the shunt-winding c^2 is connected, might be made continuous with each other, as shown in Fig. 9, without altering the operation of the switch, and the same is true of the plates d^7 and d^{10} . 80

The shaft b' of the winding-drum is screw-threaded at one end, and on the threaded portion is mounted a traveling gear b^4 , whose teeth mesh with gear-teeth d^{17} , formed on the shipper-pulley. The hub of the gear b^4 is formed with projecting bosses, and on the shaft b' are secured two collars b^5 b^6 , having bosses adapted to engage those on the gear. The gear travels longitudinally between the collars b^5 b^6 , being ordinarily held from rotating by its engagement with the teeth on the shipper-pulley, and after a certain number 95 of revolutions of the winding-drum in either direction the gear is engaged by one of the collars and is rotated so as to rotate the shipper-pulley, and thus automatically open the switch. 100

I provide in connection with the shipper mechanism a device for automatically stopping the hoisting apparatus if the elevator-car should become stuck in the shaft or obstructed in its descent, or if for other reason 105 the hoisting-cable should slacken. This device is illustrated in Figs. 11 and 12, in which o is a horizontal shaft journaled in brackets o' o' , attached to the bed a . To said shaft are secured an arm p , carrying at its upper end 110 a shaft p' , on which slides a traveling sheave p^2 , which bears against one section of the hoisting-cable b^3 , a weight-arm q , carrying a weight q' , and an arm r , carrying at its upper end a shaft r' , on which are mounted two idle-gears r^2 and r^3 , one mounted opposite the traveling gear b^4 and the other opposite a driving-gear b^7 , secured to the end of the winding-drum shaft b' . The gear r^3 , as here shown, 115 is loosely mounted on the shaft r' , and its hub is formed with one half r^4 of a claw-clutch. The other half r^5 of said clutch is splined to the shaft and is normally held in engagement with the half r^4 by means of a spring r^6 , abutting against a fixed collar r^7 . The gear r^2 is 120 fixed to the shaft r' . It will be seen that by the aid of the weight q' the cable-roller p^2 is held against the cable b^3 and the idle-gears r^2 r^3 are actuated in the direction of the gears b^4 b^7 , but are separated therefrom so long as 125 the weight of the elevator-car keeps the cable taut. If for any reason the cable slackens while unwinding, the idle-gears are thrown 130 into mesh with the gears on the drum-shaft

and motion of rotation is transferred from the driving-gear b^5 to the gear b^4 through the said idle-gears, thereby moving the shipper-pulley and throwing the switch open, so as to stop the motor. The motor may be started again by the operator in a direction to raise the car by manipulating the shipper-rope in the ordinary manner, the teeth of the clutch $r^4 r^5$ being inclined in such a direction that the gear r^2 rotates independently of the gear r^3 when the shipper-pulley is moved in a car-hoisting direction. In practice I have found it desirable to so construct the gears that r^3 is brought into mesh with b^5 before r^2 meshes with b^4 , since otherwise two teeth of the latter two gears might ride on each other and prevent any of the gears from intermeshing. In the present instance the teeth of the gear r^2 are made slightly shorter than their normal length by cutting off their crowns. The effect of this is shown in Fig. 12, for when the gears are brought together their pitch-lines, whose location is indicated by the lines $x^3 x^2$ and $y^2 y^3$, would naturally coincide or "oscillate" simultaneously; but the short teeth of gear r^2 prevent it from meshing with its opposed gear b^4 until after the other two opposed gears have come into mesh.

I do not wish to be confined to the exact construction herein set forth, as the same may be variously modified without departing from the spirit of my invention.

I claim—

1. In an elevator mechanism, a hoisting apparatus including a winding-drum and an electric motor for actuating the same, a rheostat connected with the motor-circuit, and mechanical devices connecting the hoisting apparatus and the rheostat, whereby the movement of the hoisting apparatus actuates the rheostat to vary the resistance in the motor-circuit.

2. In an elevator mechanism, a hoisting apparatus including a winding-drum and an electric motor for actuating the same, a rheostat connected with the motor-circuit, and a friction device connected with the hoisting apparatus and operating upon the rheostat, whereby the movement of the hoisting apparatus actuates the rheostat to vary the resistance on the motor-circuit.

3. In an elevator mechanism, a hoisting apparatus including a winding-drum and an electric motor for actuating the same, a rheostat connected with the motor-circuit, a shipper mechanism, and mechanical devices connecting the rheostat with the hoisting apparatus and with the shipper mechanism, whereby both of the latter may actuate the rheostat to vary the resistance in the motor-circuit.

4. In an elevator mechanism, a hoisting apparatus including a winding-drum and an electric motor for actuating the same, a rheostat connected with the motor-circuit, a shipper mechanism, a connection between the rheostat and the shipper mechanism, and a frictional connection between the rheostat

and the hoisting apparatus, whereby both the shipper mechanism and the hoisting apparatus may actuate the rheostat to vary the resistance in the motor-circuit.

5. In an elevator mechanism, a hoisting apparatus including a winding-drum and an electric motor for actuating the same, a rheostat connected with the motor-circuit, a shipper mechanism, a driving mechanism connected with the rheostat, a lost-motion device furnishing connection between said driving mechanism and the shipper mechanism, and a frictional connection between the driving mechanism and the hoisting apparatus, the arrangement being such that both the hoisting apparatus and the shipper mechanism may actuate the rheostat to vary the resistance in the motor-circuit.

6. In an elevator mechanism, a hoisting apparatus including a winding-drum and an electric motor for actuating the same, a shipper mechanism, a resistance connected with the motor-circuit, a switch controlling the motor-circuit and actuated by the shipper mechanism, and devices connected with the hoisting apparatus and with the shipper mechanism and controlling the resistance, whereby the movement of the shipper mechanism in a certain manner closes the switch with the resistance in the motor-circuit, and the resulting movement of the hoisting apparatus causes the resistance to be gradually cut out.

7. In an elevator mechanism, a hoisting apparatus including a winding-drum and an electric motor for actuating the same, a rheostat connected with the motor-circuit, a rotary member having a positive connection with the rheostat, and a second rotary member having a positive connection with the hoisting apparatus and having a frictional connection with the first rotary member, whereby the movement of the hoisting apparatus actuates the rheostat to vary the resistance in the motor-circuit.

8. In an elevator mechanism, a hoisting apparatus including a winding-drum and an electric motor for actuating the same, a rheostat connected with the motor-circuit, a rotary shaft positively connected with the rheostat, a stop member on said shaft, and a shipper-pulley having separated stops adapted to engage the stop member on the shaft, the arrangement being such that the shipper-pulley may be moved to actuate the rheostat and vary the resistance in the motor-circuit, and may also be moved independently of said rheostat.

9. In an elevator mechanism, a hoisting apparatus including a winding-drum and an electric motor for actuating the same, a rheostat connected with the motor-circuit, a switch controlling the motor-circuit and having a movable member, a rotary shaft positively connected with the rheostat, a stop member on said shaft, and a shipper-pulley carrying the movable member of the switch and hav-

ing separated stops adapted to engage the stop member on the shaft, whereby the shipper-pulley may be moved to actuate the rheostat and vary the resistance in the motor-circuit, and may also operate the switch independently of the rheostat.

10. In an elevator mechanism, a hoisting apparatus including a winding-drum and an electric motor for actuating the same, a rheostat connected with the motor-circuit, a rotary shaft, a shipper-pulley having provisions for rotating said shaft, a friction-disk secured to the shaft and positively connected with the rheostat, a second friction-disk loosely 15 mounted on the shaft and movable longitudinally thereof, the said second disk being in contact with the first disk and positively connected with the hoisting apparatus, and means for regulating the pressure between 20 the friction-disks to vary the amount of friction between them.

11. A compound-wound motor, and a reversing-switch therefor comprising fixed contacts or terminals connected to the source of 25 current-supply, the shunt-winding of the motor-field, the series winding of said field, and the armature-winding, and two movable conductors adapted to contact with the fixed terminals in two different arrangements, by 30 which current is sent in the same direction through the field-windings but in reverse directions through the armature-windings.

12. A compound-wound motor, and a reversing-switch therefor comprising two sets 35 of fixed members, each consisting of contacts or terminals connected respectively to the line or source of current-supply, the shunt-winding of the motor-field, the series winding of said field, and the armature-winding, 40 and two movable conductors, one of which is adapted to connect terminals of the line, shunt-winding, and armature-winding in either set, and the other of which is adapted to connect terminals of the series winding 45 and armature-winding in either set.

13. A compound-wound motor, and a reversing-switch therefor comprising two sets of fixed members each consisting of contacts or terminals connected respectively to the 50 line or source of current-supply, the shunt-winding of the motor-field, the series winding of said field, and the armature-winding, and two movable conductors, one of which is adapted to connect terminals of the line, 55 shunt-winding, and armature-winding in either set, and the other of which is adapted to connect terminals of the series winding and armature-winding in either set, the construction and arrangement being such that 60 in opening the switch the first-mentioned conductor breaks contact with the line-terminal while it and the other movable conductor still complete a circuit through the shunt, series, and armature windings.

65 14. The combination of the line-electrodes, the motor having field and armature windings, and a reversing-switch having terminals or

contacts connected with the motor-windings and the line-electrodes, said switch having two positions in which the said terminals are 70 arranged to run the motor in reverse directions, the line-terminals being short so that contact is broken first thereat, the remaining switch-terminals being so arranged that when the line is thus disconnected, a closed circuit 75 is preserved through the motor-windings and said terminals.

15. In an elevator mechanism, a hoisting mechanism including a winding-drum and a motor, a mechanism for controlling said motor including a shipper-pulley having a gear on its shaft, a gear operated by the hoisting mechanism, a device adapted to connect the said two gears and cause the latter to drive the former and operate the shipper mechanism, and a pivotal bracket carrying said device and normally sustained by the hoisting-cable so as to hold said device out of operative position.

16. In an elevator mechanism, a hoisting 90 mechanism including a winding-drum and a motor, a motor-controlling shipper mechanism including a shipper-pulley having a gear on its shaft, a gear operated by the hoisting mechanism, and a device operated by the 95 slackening of the hoisting-cable and adapted to connect the said two gears, said device being constructed to effect a positive connection whereby the last said gear drives the first 100 said gear and operates the shipper mechanism when the hoisting mechanism is moving in a car-lowering direction, and said device having provisions for permitting the movement of the shipper-pulley in a car-hoisting direction, when the device is in operative position.

17. In an elevator mechanism, a hoisting mechanism including a winding-drum and a motor, a shipper mechanism including a shipper-pulley and a spur-gear whose rotation operates the same, a spur-gear operated by the hoisting mechanism, an opposed spur-gear mechanism adapted to effect a driving connection between the said two gears, and a cable-operated carrier supporting said mechanism and movable laterally toward and from the said two gears.

18. In an elevator mechanism, a hoisting mechanism including a winding-drum and a motor, a motor-controlling shipper mechanism, and a device for effecting a driving connection between the hoisting and shipper mechanisms, said device including a bracket movable by the slackening of the cable, a pair of gears carried by said bracket and adapted 125 to engage respectively with the hoisting and shipper mechanisms, and a clutch connecting said gears and having inclined teeth and a yielding portion whereby the hoisting mechanism may operate the shipper mechanism 130 when the former moves in a car-lowering direction, while movement of the latter in a car-hoisting direction is permitted.

19. A gear mechanism comprising a pair of

relatively rotatable gears, one of which is a driving-gear, a second pair of gears opposed to the first pair and having a connection whereby one may rotate the other, and means 5 for bringing one pair of gears into mesh with the other pair, whereby the driving-gear of the first pair is caused to drive the other gear of said pair, the gears being arranged so that when brought together their pitch-lines would 10 coincide simultaneously, while their teeth are

so constructed that the driving-gear engages its opposed gear before the other two gears come in contact.

In testimony whereof I have affixed my signature in presence of two witnesses.

MARTIN B. McLAUTHILIN.
